(57) **CLAIM**

The ornamental design for a hand stamp, as shown and described.

DESCRIPTION

FIG. 1 is a front perspective view of a hand stamp showing my new design;

FIG. 2 is a front elevation thereof, the side opposite being a mirror image;

FIG. 3 is a left side elevation, the side opposite being a mirror image;

FIG. 4 is a top plan view thereof;

FIG. 5 is a bottom plan view thereof;

FIG. 6 is a perspective view of the design shown in FIGS. 1 through 5 in a compressed condition;

FIG. 7 is an affront elevation thereof, the side opposite being a mirror image;

FIG. 8 is a left side elevation thereof, the side opposite being a mirror image; and,

FIG. 9 is a bottom plan view thereof.

The back view elevational view of the stamper of FIG. 1 is a mirror image of FIG. 2.

The back view elevational view of the stamper of FIG. 6 is a mirror image of FIG. 7.

The right side elevational view of the stamper of FIG. 1 is a mirror image of FIG. 3.

The right side elevational view of the stamper of FIG. 6 is a mirror image of FIG. 8.
